UNITED STATES PATENT OFFICE.

FRANK A. KLAINE, OF NEWPORT, KENTUCKY.

DESIGN FOR A COOKING-RANGE.

SPECIFICATION forming part of Design No. 26,526, dated January 12, 1897.

Application filed November 21, 1896. Serial No. 613,032. Term of patent 3½ years.

To all whom it may concern:

Be it known that I, FRANK A. KLAINE, a citizen of the United States, and a resident of Newport, in the county of Campbell, State of Kentucky, have invented a certain new and useful Design for Cooking-Stoves, of which the following is a specification.

My design for a cook stove or range is fully illustrated in the accompanying drawing, which is a perspective view of the same.

The leading features of my design are the foliated scrollwork formed on the base, the scrollwork on the oven-door and the damper-slide, and the support for the mantel-shelf.

The base is quadrangular in form and mounted on suitable legs. The edge of the base is ornamented with a scroll of the pattern shown, there being a leaf-like form a extending down each leg, and there being two counterpart oppositely-extending scrolls a' a'' extending along the front side of said base edge from about the center to opposite corners. On the side edges of the base two oppositely-extending scrolls a^3 a^4 are intertwined with and connected by an intermediate scroll-like form a^5 .

The oven-door B has a centrally-arranged shield-like space B', surrounded by scrolls, there being two main scrolls, each having one member extending partly over the top of said space B', as at b , and another member b' extending along one side and partly under said space B'. The inner adjacent ends of the

members b of said scrolls are separated by an elliptical-shaped form b^2 , while the lower portions of the members b' of said scrolls are intertwined with another scroll or scrolls, b^3 .

Ornamental shield-like spaces surrounded by scrollwork are formed on the fire-door C and the ash-door D, as at c d .

The damper-slide is ornamented with a series of connected elliptic curves e .

The mantel-shelf F has compound-curved supports f' , connected by a perforated connection f with the back plate at their centers, and said mantel-shelf is surmounted by an ornamental plate G, having two main scrolls g g' , arranged on opposite sides of and almost surrounding a central figure h of the form shown.

What I claim is—

1. The design for a cook stove or range substantially as herein shown and described.
2. In a design for a cook stove or range the oven-door as herein shown and described.
3. In a design for a cook stove or range the mantel-support as herein shown and described.
4. In a design for a cook stove or range the damper-slide herein shown and described.

In testimony whereof I hereunto set my hand in presence of two witnesses.

FRANK A. KLAINE.
